UNITED STATES PATENT OFFICE.

JOSEPH Perna, Jr., of Philadelphia, Pennsylvania.

RHEOSTAT SWITCH.

Application filed July 7, 1923. Serial No. 650,084.

To all whom it may concern:

Be it known that I, JOSEPH Perna, Jr., a citizen of the United States, residing at Philadelphia, in the county of Philadelphia and State of Pennsylvania, have invented new and useful Improvements in a Rheostat Switch, of which the following is a specification.

My invention relates to new and useful improvements in a variable wall switch, and has for its primary object to improve the construction of such devices in order that they will be compact, substantial and relatively inexpensive in the cost of manufacture.

Another object of the invention is to provide an exceedingly simple and effective device of this character whereby the electric current passing therethrough may be readily and easily controlled to vary the intensity of a light or lights supplied with the electrical energy passing through the switch.

A further object of the invention is to provide the rheostat or coil as the rotary member and also to provide unique connections between the rotary and stationary members.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:—

Fig. 1, is an outer face or end view of a switch embodying my improvements, a portion of the knob being broken away.

Fig. 2, is a longitudinal sectional view thereof.

Fig. 3, is an inner end view of the body or casing with the cover and switch elements removed.

Fig. 4, is an inner end view of the rheostat or rotor element.

Fig. 5, is a face view of the contact member coacting with the rotor.

Fig. 5^a is an edge view of the contact member.

Fig. 6, is a face view of one of the conductors.

Fig. 7, is an edge view thereof.

Fig. 8, is an edge view of the bridge.

Fig. 9, is a face view thereof.

In carrying out my invention as here embodied, 2 represents a body or casing produced from any suitable insulating material but preferably of porcelain and this casing has a chamber 4 having an opening 5 leading thereto at the inner end and a hole 6 communicating with said chamber at the outer end. The opening 5 is normally closed by a cover, and if this cover is of metal a strip of insulating material 8, such as paper, is interposed between the cover and the casing.

In the chamber 4 of the casing are located two screws or bolts 9 and 10 directly opposite each other which pass through suitable lugs 11 and 12 with the heads of the screws or bolts in recesses 13 while the nuts 14 on said screws or bolts for holding them in place are set in recesses 15.

Within the chamber 4 is located a bridge 16 held in a stationary position by means of the screws or bolts 9 and 10 on which said bridge is mounted and said bridge is of suitable insulating material such as porcelain.

The screw or bolt 10 is adapted to be connected with the wire or conductor of an electric circuit and in order to carry this current from the screw or bolt 10 a conductor 17 is mounted on the underside of the bridge 16 and surrounds the screw or bolt 10 and said contact member 17 is held in place by a screw 18 passing through the bridge 16 and connected with a contact strip 19. On top of the bridge 16 is mounted a contact member 20 having a hole of sufficient size for the passage of the screw 18 to prevent electrical contact with said screw and between the contact member 20 and the contact strip 19 are mounted a plurality of insulating washers 21 of mica or other suitable material which thereby space the contact strip 19 from the contact member 20. From the contact member 20 runs a conductor 22 on top of the bridge 16 and surrounding the screw or bolt 9 so as to form an electrical contact in order that the screw or bolt 9 may be used as a conductor to which a wire or other conductor of the electrical circuit may be attached.

The contact member 20 includes a pair of oppositely disposed resilient contact arms 23 which are located in the path of travel of a series of spaced contact points 24 on the inner end of the rotor 25, each of said contacts being connected with different points of the resistance wire 26 embedded

- in suitable insulating material and forming the rheostat or coil while said resistance wire or coil of the rheostat is connected at one end to the metal tube 27 also forming 60
 5 a part of the rotor and acting as the complementary member to the contact strip 19. The rheostat element may be enclosed in a suitable jacket 28 which also forms a part of the rotor and has an outer wall 29 either
 10 in the form of a reduced strip or occupying the entire area of the space between the side walls of the jacket. A suitable knob 30 is inserted through the hole 6 in the porcelain casing and connected with the end wall 29
 15 of the jacket in any suitable manner as by threaded connection therewith, said knob preferably being formed of insulating material such as hard rubber with a threaded shank embedded for threaded connection
 20 with the end wall 29.

In practice this switch is placed in the ordinary wall box 31 illustrated in Fig. 2 and covered with a suitable cap, not shown, which is fastened to the flanges of the wall 25 box in ordinary practice, it being understood that the conductor wires of the electrical circuit are first attached to the screws or bolts 9 and 10 so that the current passes through the screw or bolt 9 then passes 30 through the conductor 22, the contact member 20 and from its spring arms 23 to the contact points of the resistance wire or rheostat and through a certain amount of the wire of said rheostat to the tube 27, the 35 contact strip 19, the screw 18, conductor 17 then through said conductor and the screw or bolt 10 to the conductor wire of the electric circuit. In order to change the amount of current passing to the point of 40 use it is only necessary to rotate the knob 30 which will then move the rotor the desired distance to bring one of the resilient fingers 23 into engagement with the desired contact point 24 on the rotor thus adding or 45 cutting out wire to or from the circuit.

Of course I do not wish to be limited to the exact details of construction as herein shown as these may be varied within the limits of the appended claims without departing from the spirit of my invention. 50

Having thus fully described my invention, what I claim as new and useful is:—

1. A rheostat switch comprising, in combination, a casing of insulating material 55 provided with a chamber, a stationary contact member within said chamber, a contact strip within said chamber, means for connecting the contact strip in an electric circuit, means for connecting the contact mem-

ber in an electric circuit and a rotor including a tube for coaction with the contact strip, a resistance wire, contact points tapped at different localities on the resistance wire, said contact points adapted to engage the contact member, a jacket surrounding the resistance wire and a knob connected to the jacket for operating the rotor. 60

2. A rheostat switch including a casing of insulating material having a chamber with 70 an opening at the rear and a hole at the front, a bridge within the chamber, screws for supporting said bridge and acting as conductors, a contact strip supported by said bridge, a contact member also supported by said bridge, conductors mounted on said bridge electrically connected with the contact strip and contact member and each with a different screw, a rotor within the casing including a resistance having 80 contact points for engagement with the contact member and also having a tube for engagement with the contact strip, and a knob projecting through the hole in the front of the casing and connected to the 85 rotor for actuating the same. 75

3. A variable wall switch including a casing of insulating material, screws mounted within said casing, a bridge of insulating material connected with said screws, a contact strip carried by said bridge, a contact member carried by said bridge, means for electrically connecting one screw with the contact strip, means for electrically connecting the other screw with the contact member, and a rotary resistance within the insulated casing and contacting with the contact strip and contact member whereby the rotation of said resistance will vary the same between the two screws. 90

4. A variable wall switch comprising a casing, a rotor within said casing, said rotor including a jacket, a concentric tube, a resistance between said tube and jacket having one end connected to the tube and having contacts each connected with a different part of the resistance, a contact strip within the rotor coacting with the tube thereof, resilient contact arms for cooperation with the contacts of the resistance, means for connecting the contact strip to one side of an electric circuit, and means for connecting the spring contact arms with the other side of an electric circuit. 100

In testimony whereof, I have hereunto affixed my signature.

JOSEPH PERRA, JR.
